T. Bell.

Raising Sunken Vessels.

Nº 17826.

Patented Jul 21, 1857.

UNITED STATES PATENT OFFICE.

THOMAS BELL, OF NEW YORK, N. Y.

ARRANGEMENT OF CAMELS FOR RAISING SUNKEN VESSELS.

Specification of Letters Patent No. 17,826, dated July 21, 1857.

To all whom it may concern:

Be it known that I, THOMAS BELL, of the city, county, and State of New York, have invented a new and useful Improvement in 5 Camels for Raising Sunken, Stranded, or Floating Vessels; and I do hereby declare that the following is a full, clear, and exact description of the same, reference being had to the accompanying drawings, forming 10 part of this specification, in which—

Figure 1, is a side elevation of a ship with camels constructed and applied to it after my invention. Fig. 2, is a plan view of the same.

15 Similar letters of reference in each of the several figures indicate corresponding parts.

The nature of my invention consists in three camels so combined and arranged relatively to each other as that each one shall 20 serve as a support for the other, and the three united shall form a bottomless dry dock, or a firm and proper shaped support for the bow and the forward portion of the vessel or the stern and after part of the same, 25 whereby the necessity of raising the vessel by taking hold of the bilge or weakest part thereof and of experiencing the great difficulty attending the getting of the attachments of the camels under the keel are 30 avoided, and the vessel can be lifted principally by the bow and stern or at points where the greatest strength exists, and only partially fore and aft, or where the least strength exists and thus much time, labor, 35 loss and danger, both to operators and the object being operated upon, avoided.

To enable others skilled in the art to make and use my invention I will proceed to describe its construction and operation.

40 A, is a ship.

B, B, are two water tight floats or tanks, each constructed with three distinct compartments which are furnished with pumps M M and intended to serve separately or 45 unitedly as camels. The end and side camels of each of the floats are of triangular form the inboard timbers of the side camels meeting in a point at the angle of the end camel, and being intersected and interlocked at the 50 base of the outer timbers of the same, by the bulk head or inboard timbers C' of the end tank. By thus uniting the camels it may be evident that a perfect system of truss work is produced and a firm and strong sup- 55 port for the vessel secured, and by having the side tanks of taper form on their inner

side a space of proper shape for the reception of the bow or stern of the vessel is secured, and by having said space open at top and bottom the necessity of passing chains etc., under the keel of the vessel is avoided. The tanks or camels when applied are united together by chains K, K, and made to clasp the bow and stern of the vessel, and should be of sufficient length and capacity to afford 60 buoyancy enough to raise and float vessels of any tonnage desired, and the inboard timbers C, C, and bulkhead C' of the camels made very heavy and strong so as to be capable of bearing any weight which may be 65 brought to bear upon them.

Operation: The camels being sunk and drawn on to each end of the sunken vessel, and secured to each other as shown in the drawing, the pumps are operated upon, 75 when submerged, by means of ropes or rods passing up from the ends of the braces of the pistons to the surface, and the water pumped out of the camels, and air admitted, to fill its place, by means of tubes. As soon as 80 the required quantity of water passes out and air takes its place the vessel begins to rise, until she rides upon the surface of the water, owing to the lifting power of the camels overbalancing the sinking power of 85 the vessel, when she may be transported by tugs or other means to her destination. In case the vessel is not sunken but simply stranded, while the water is low the tanks are to be drawn on to the vessel and secured 90 to each other, so that when the rise of the tide occurs they shall take the weight of the vessel and lift her off the bottom so that she may be readily transported, without the use of pumps, to her place of destination. 95

There are several very important advantages derived from the use of my improvements.

1st. It is practicable under all circumstances, which is not the case with any other 100 camel heretofore known and used. It is practicable under all circumstances, 1st, because it does not require to be fastened on to the vessel by chains or hooks or other means; 2nd, because it does not require to be 105 pressed under the keel or over or through the vessel; 3rd, because it is durable and sufficiently strong to bear all the rough usages of the sea, and should the winds be strong or ice collect so as to endanger the 110 safety of the vessel, after she has been raised to the surface, by simply letting water into

the camels she may be lowered again on bottom and thus be placed beyond the reach of their destructive influence.

2nd. When the vessel arrives at the dry dock which is to take her on for repairs she may be righted up so as to take the list out of her or to cause her to set on an even keel, or she may be elevated at one end and lowered at the other by drawing off, or letting water 10 into the camels. This is a very important feature and renders my invention a very useful auxiliary to the dry dock.

3rd. The vessel with my camels applied can enter readily an ordinary dry-dock which 15 is not the case when side camels or vessels are employed.

4th. When the operators meet with any obstruction to their progress, the camels can be sunken or anchored, and kept in safety 20 until all things are made ready.

5th. It is always in condition for immediate and speedy application and use, not liable to get out of repair or sustain damage, and is very simple and cheap in construction 25 compared with anything else for the same purpose heretofore known.

I am aware that J. N. Winslow obtained a patent Aug. 20, 1850, on a device for raising vessels, but his device can only be applied 30 when a vessel is afloat and even then the thickness of the machine under the vessel's keel adds to the draft of water that would otherwise be required and therefore the vessel must be lifted higher than is necessary 35 with my camels in order to carry her in the same depth of water.

I am also aware that O. T. Williams obtained a patent Feby. 24, 1852, for a device for accomplishing a similar result; but his 40 contrivance can only be applied by hooking into a vessel at or near her bilge, which is the weakest part of the ship, and the only part that can be hooked into to lift directly up, and the unavoidable tendency of lifting

with Mr. Williams' hooks is to haul out- 45 board instead of inboard. They therefore could not hold to the vessel, but admitting they did hook into the vessel so that the hooks did hold them, the plank that the hooks hooked into would most certainly 50 come off, as there are but a few spikes and pins that hold a plank on; but admit the hooks and planks both hold and keep their place there is not sufficient strength in his attached frame as he constructs it; but admitting all to hold and have sufficient strength, in a few hours by the motion of the sea and strain on his india rubber it must unavoidably soon wear or chafe through even should he be so lucky as to prevent the 60 rubber coming in contact with bolts or spikes or something to pierce it, which would probably happen and therefore render his means entirely valueless.

I do not claim broadly the use of camels 65 for raising sunken vessels irrespective of the peculiar construction shown and described in my specification, but

What I do claim as my invention and desire to secure by Letters Patent, is—

The arrangement of camels herein described, whereby great strength is secured to support a vessel while being raised and transported, and whereby the vessel will be lifted principally by the bow and stern, or 75 where the greatest strength exists; and only partially fore and aft, or where the least strength exists; and whereby all the inconveniences attending the application and use of those devices which require that some of 80 their parts shall be passed under the keel or over or through the vessel are avoided, and other numerous benefits secured; substantially as set forth.

THOS. BELL.

Witnesses:

CHARLES L. BARRITT,
JOHN C. WAGSTAFF.
